UNITED STATES PATENT OFFICE.

CHARLES EDWIN ROSE, OF WILLENHALL, ENGLAND.

STAIR CARPET AND LIKE FASTENING.

Application filed August 31, 1925, Serial No. 53,528, and in Great Britain January 10, 1925.

This invention relates to means for securing in position carpets or other like coverings to stairways. In the fixing of stair carpets, it is usual to employ rods which extend across the carpet at the angles between the treads and the risers of the stairs and are secured by angle brackets such as are generally known as stair rod eyes. The present invention appertains to the type in which independent clip arms are arranged to project over opposite edges of the carpet.

10 The invention consists of a bracket provided with a rear cavity and a clip arm with a forked engaging end having an endwise movement upon the bracket into a wedge fit therewith.

The invention is described with reference to the accompanying drawings in which

20 Fig. 1 is a longitudinal section on line *a. a.* of Fig. 2 of one form of the device.

Fig. 2 is a transverse vertical section on line *b. b.* of Fig. 1.

Fig. 3 is a longitudinal section of a modification on line *c. c.* of Fig. 4 showing the 25 employment of a spring.

Fig. 4 is a transverse vertical section on line *d. d.* of Fig. 3.

Fig. 5 is a longitudinal section of a further modification on line *e. e.* of Fig. 6.

30 Fig. 6 is a transverse vertical section on line *f. f.* of Fig. 5.

Fig. 7 is a longitudinal section of another modification on line *g. g.* of Fig. 8.

Fig. 8 is a transverse vertical section on 35 line *h. h.* of Fig. 7.

Fig. 9 is a front view of the bracket separately.

Referring to Figs. 1 and 2, an attachment bracket 1 is adapted to fit snugly in 40 the corner at the junction of the tread and riser of the stairway, and is formed at the back with an undercut recess or cavity 2 of an angle shape cross sectionally, or of any other suitable shape as required, said recess 45 or cavity being open at the inward end and preferably closed at the outward end by a side cheek 3.

A clip arm or clamping piece 4 is formed or provided at its outward part and at its 50 underside with an outwardly projecting tongue piece or member 5 which is cranked or bent from the back of the clip arm or clamping piece 4 and is longitudinally disposed and laterally spaced therefrom. Said 55 tongue piece or member 5 has inclined sides 5^a upon its inner face opposite the rear side

of the clip arm for clamping piece 4 corresponding to the shape of the recess or cavity 2, or where the recess or cavity is of a different shape, the tongue piece or member may 60 be of corresponding section to fit the said recess.

The clip arm or clamping piece 4 is connected with the bracket 1 by advancing the tongue piece or member 5 into the recess or 65 cavity 2 of the same, and the outward part of the arm upon the front plate of the bracket 1. There is just sufficient clearance between the clip arm or clamping piece 4 and the tongue piece or member 5 for said arm 70 4 to pass over the bracket 1 and engage same with a wedge fit.

Only a single endwise movement of the clip arm or clamping piece in an outward direction is needed to effect this connection, 75 and only a single endwise movement of the clip arm or clamping piece in a converse direction is necessary for its retraction from the bracket 1.

Referring now to Figs. 3 and 4, a spring 80 blade or element 6 is attached to the rear of the bracket 1 and extends across the back of the recess or cavity 2. The spring blade or element 6 at its free end is slightly bent. The tongue piece or member 5 is preferably 85 provided with a notch 7 across its rear side, or alternatively to a notch, it may be a projection, as will be understood.

As the clip arm or clamping piece 4 is brought into engagement with the bracket 1, 90 the spring blade or element 6 bears against the underside of the tongue piece or member 5 and snaps into the notch 7 or over the projection of the tongue piece or member and thereby securely holds the arm 4 to the 95 bracket 1. The construction is otherwise the same as shown in Figs. 1 and 2.

In the modified form shown in Figs. 5 and 6, a spring element 8 is located across the front of the bracket 1 in longitudinal 100 alignment with the clip arm 4 and is bent at its middle or intermediate portion to engage a depression 9 in the underside of the clip arm or any equivalent projection in lieu of the said depression, the free ends of the spring element 8 being passed through apertures 10 for connection to the said bracket. The spring element 8 thereby holds the clip arm or clamping piece 4 securely to the bracket. 105

In the modified form shown in Figs. 7 to 110 9, the spring element 11 is arranged at the

front of the bracket 1 in a transverse disposition relatively to the clip arm or clamping piece 4 and is secured by its bent free ends to said bracket. The spring element 11 engages a cross notch 9^a in the underside of the clip arm 4.

What I claim is:—

1. A stair carpet or like fastening, comprising a bracket formed with a rear cavity, a spring element located at the back of the bracket, and extending across the cavity, and a clip arm with a longitudinally extending tongue piece spaced back therefrom, the said arm having an endwise movement on to the bracket with the tongue piece entered in the cavity of the bracket and the opposed end of the arm extending over the front of the same, and with the spring element bearing against the clip arm.
2. A stair carpet or like fastening, comprising a bracket with an undercut recess at the rear side, a clip arm with a longitudinally projecting tongue piece bent from the back thereof and outwardly directed therefrom, and a spring element secured to the bracket, said arm having an endwise movement upon the bracket with the tongue piece entered in the recess at the back of the bracket and the spring element abutting against the arm.
3. A stair carpet or like fastening, comprising a bracket with an undercut recess at the rear side, a clip arm with a longitudinally cranked tongue piece laterally spaced therefrom, and a spring element secured to the bracket, said clip arm having an endwise movement upon the bracket to bring the tongue piece into engagement with its rear recess and the arm over the front plate of the bracket, with the spring element abutting against the clip arm.
4. A stair carpet or like fastening, comprising the combination with a bracket for attachment to the stairway of a clip arm formed at one end with an outwardly and longitudinally extending tongue piece offset therefrom so as to provide with the arm a bifurcated part and a spring element for

the bracket bearing against the arm for effecting a wedge grip of the arm upon the bracket.

5. A stair carpet or like fastening, comprising the combination with a bracket for attachment to the stairway of a clip arm formed with a rearwardly bent and longitudinally projecting tongue piece laterally spaced therefrom and acting in conjunction with the arm to present a bifurcated end, and means upon the front of the bracket longitudinally of the clip arm abutting against the adjacent end of the clip arm for effecting a wedge fit upon the bracket.

6. A stair carpet or like fastening, comprising the combination of a bracket with an angled recess for attachment to the stairway, a clip arm forked or bifurcated at one end by forming the same with a longitudinally projecting tongue piece spaced back from the arm, said tongue piece having bevel sides to engage with the angled recess of the bracket, and means whereby the furcations are adapted to effect a wedge grip upon the bracket.

7. A stair carpet or like fastening comprising a bracket formed with an undercut recess open at the inward end of the bracket, and a clip arm forked at one end by forming it with a longitudinally projecting tongue piece spaced back from the arm and engaging the surfaces of the recess for effecting a wedge grip on the bracket.

8. A stair carpet or like fastening comprising a bracket longitudinally formed with an undercut recess angular in cross section and open at the inward end of the bracket, and a clip arm forked at one end by forming it with a longitudinally projecting tongue piece spaced back from the arm and having bevelled sides to engage the surfaces of the angled recess for effecting a wedge grip on the bracket.

In testimony whereof, I have signed my name to this specification at Birmingham, England, this 24th day of July, 1925.

CHARLES EDWIN ROSE.
